UNITED STATES PATENT OFFICE.

ROBERT C. GRUBER, OF SPRING CITY, PENNSYLVANIA.

STOP-MOTION FOR KNITTING-MACHINES.

1,071,910.

Specification of Letters Patent.

Patented Sept. 2, 1913.

Application filed June 24, 1912. Serial No. 705,603.

To all whom it may concern:

Be it known that I, ROBERT C. GRUBER, a citizen of the United States, residing at Spring City, in the county of Chester and

5 State of Pennsylvania, have invented certain new and useful Improvements in Stop-Motions for Knitting-Machines; and I do declare the following to be a full, clear, and exact description of the invention, such as 10 will enable others skilled in the art to which it appertains to make and use the same.

This invention relates to improvements in automatic stop motions for knitting machines.

15 The object of the invention is to provide a simple and efficient stop motion device operable reliably on encountering a hole in the fabric to instantly stop the machine.

Another object of the invention is to provide 20 a device of this class which may be applied to any circular knitting machine having a revolving needle cylinder and dial and a central stud, and which positively stops the machine instantly when, for any reason, 25 a stitch is dropped or a hole in the fabric occurs, thereby dispensing entirely with menders and latchups.

With these and other objects in view, the 30 invention consists of certain novel features of construction, and the combination and arrangement of parts as will be more fully described and claimed.

In the accompanying drawing: Figure 1 is a side elevation of a portion of a knitting 35 machine equipped with this attachment; Fig. 2 is a vertical section of a portion of a circular knitting machine equipped with this improved device, said device being shown in elevation; Fig. 3 is a perspective 40 view of the attachment detached. Fig. 4 is a top plan view of the plate or casting of the attachment, partly in section; Fig. 5 is a bottom plan view thereof; Fig. 6 is a side elevation of said casting applied; Fig. 45 7 is a longitudinal vertical section thereof on line 7—7 of Fig. 4. Fig. 8 is a transverse section on line 8—8 of Fig. 4.

In the embodiment illustrated, a circular 50 knitting machine A is shown provided with the usual cross bars B, having a central collar C that receives and holds a center stud D, here shown in the form of a tube, said tube forming a support for the attachment constituting this invention and 55 which will presently be described. A drip cup E, which is usually secured to the cen-

ter stud in longitudinal alinement therewith, is here shown offset therefrom to provide for the passage through the tube D of a portion of the stop motion device. 60

This stop motion device, which constitutes this invention, comprises a plate or casting 1 of any suitable shape, here shown substantially rectangular with one end rounded and which is provided with an aperture 2 for receiving the center tubular stud D to which it is shown secured by a set screw 3. A strip 4, preferably of light spring steel, is adjustably mounted on the rounded end of the plate or casting 1 and is here shown provided with longitudinal slots 5 at its opposite ends by means of which the strip or band 4 is secured to the opposite side edges of the plate 1 by screws 6 which pass through said slots 5 and engage screw 75 threaded sockets in the side edges of the plate. This strip or band 4 may be adjusted toward or away from the plate or casting 1 a suitable distance to adapt the attachment for use with tubular fabric of 80 different diameters, and it is designed for the purpose of spreading and guiding the fabric and causing it to run evenly over the hole detecting element or feeler to be described. The tubular fabric E' is usually 85 drawn through rollers to flatten and smooth it before it is wound on a spindle and, consequently, this curved band 4 is necessary to prevent the collapse of the fabric when passing over the hole detecting element to 90 insure the accurate working of said element. This curved band or guide 4 has a longitudinal slot 7 arranged midway of its ends for a purpose to be described.

The hole detecting element or feeler arm 95 is shown in the form of a blade or pin 8 pivotally mounted intermediately of its ends on the lower face of the plate 1, and is adapted to swing freely in a horizontal plane. One end of this arm or blade 8 projects over said aperture 2 and extends nearly across the aperture, and the other end extends through the slot 7 of the band 4 and is provided with a finger 9, here shown slightly rounded and in hook shape, and 100 which is adapted to bear or feel against the inner face of the knit tube E' as the fabric rotates and to engage in any hole therein such as may be formed by the breakage of a knot in the yarn, the dropping of a stitch 110 or run down, caused by imperfect needles. This arm or blade 8 is adjustably mounted

on the casting or plate 1 to permit it to be moved outward and inward to adapt it for use with fabric tubes of varying diameters, and the plate is here shown perforated for this purpose. A light coiled spring 10 is secured at one end to the plate 1 and at its other end to the feeler arm 8, and is designed to return the arm to operative position after it has been oscillated by engagement with 5 a hole in the fabric, as will be hereinafter described. A stop rod 11, slightly longer than the tubular bearing stud D, extends through said stud and is adapted to slide freely therein with its lower end normally resting on the inner end of the arm 8, which is arranged in the path of said rod. An arm 12 is secured at one end to the upper end of the rod 11 and extends laterally therefrom, and a light coiled spring 13 connects 10 this arm with the stud D and exerts its tension to force said rod 11 downwardly. A link 14 depends from the free end of said arm 12 and connects it with a crank rod 15. This crank rod 15 has an arm 16 mounted 15 for longitudinal adjustment thereon, and which is adapted to extend in position to engage a needle guard or trip lever G, which controls the belt shifting mechanism, when said crank arm is actuated and thereby stops 20 the machine. This needle guard or trip lever is commonly employed on circular knitting machines having a cylinder and dial and is termed a "needle protector," as it is usually arranged in proximity to the 25 needles in order that should any punching or imperfection occur near the needles the bunch will engage the trip lever through which mechanism to be described is actuated to shift the belt from the fast to the loose 30 pulley of the machine, thereby immediately stopping the machine to permit the imperfection in the fabric to be repaired.

The crank rod 15 lies, when the device is applied, directly under the cross bar B extending toward one of the needle guards with its arm 16 positioned to throw said guard off and thereby shift the belt and stop the machine when the crank shaft or rod 15 is turned. Clamps 17 are mounted 45 on the rod 15 and are adapted to be connected with the cross bar B by set screws 18 for holding the rod in operative position.

The mechanism for shifting the belt 19 from the fast pulley 20 to the loose pulley 50 21 comprises the needle guard G, which is pivotally mounted on the upper side of an upright supporting bracket 22 fastened on the base plate or table of the machine, and which normally engages a notch 23 formed 55 in one side of a vertically moving spring actuated trip rod 24. The vertically movable trip rod 24 is arranged to work through guide openings in the bracket 22 and the base plate or table of the machine and an 60 actuating spring 25 is arranged thereon be-

low the base plate which tends to normally move the rod downward and against the upper side of a latch arm 26. The latch arm 26 is pivotally supported at one end as at 27 on one of the supporting uprights 70 28 of the machine, and the free end of the latch arm has connected thereto one end of a spring 29 which is weaker than the spring 25, and the other end of which spring 29 is fastened to the under side of the base plate of the machine to provide for normally holding the arm 26 in an elevated position, so that it will engage in a catch notch 30 formed in the inner end of the shifting rod 31. The shifting rod 31 is suitably supported at one side of the fast and loose pulleys 20 and 21, respectively, which are mounted on the usual drive shaft which imparts motion to the knitting machine, and said rod 31 is normally moved in one direction by an actuating spring 32 arranged thereon. At a suitable point the rod 31 has connected thereto the usual loop shifting wire 33, which engages the drive belt of the machine to provide for shifting the same 80 from the fast to the loose pulley, and thereby providing means for stopping the machine. At this point it will be noted that, while the wire 33 constitutes the belt shifter proper, the belt shifting mechanism comprises the group of parts G, 24, 26, 31 85 and 33.

In the operation of the device the parts being in normal position as shown in Fig. 1 with the fabric running smoothly over 100 finger 9 and the lower end of rod 11 resting on arm 8, should a hole occur in the fabric for any reason, the finger 9 will immediately project thereinto and the turning of the fabric will swing the arm 8 laterally, 105 thereby moving its inner end from under the rod 11 which immediately drops by the force of gravity and the tension of the spring 13, whereby the crank rod 15 is simultaneously turned and the arm 16 thereof 110 engaged with the adjacent needle guard G, thereby throwing it out of engagement with the notch 23 in the rod 24 and permitting the belt shifting mechanism to operate to shift the belt from the fast to the loose 115 pulley and thereby instantly stop the machine. The break in the fabric is then repaired and the cause corrected. The rod 11 is then raised, which permits the spring 10 to swing the arm 8 back to its normal 120 position with its inner end under the rod 11, whereby the arm 16 of the crank shaft 15 is held out of engagement with the needle guard and the machine may be again started.

It is thought that the advantages of this 125 improved simple device will be understood without further explanation, as the disadvantages of dropping stitches and breaks in the fabric which render the goods imperfect are well-known.

From the foregoing description taken in connection with the accompanying drawings, the construction and operation of the invention will be readily understood without requiring a more extended explanation.

Various changes in the form, proportion and the minor details of construction may be resorted to without departing from the principle or sacrificing any of the advantages of this invention as defined and claimed.

I claim as my invention:

1. The combination with a knitting machine having a central stud, of a rod mounted to slide longitudinally in said stud, a pivotally mounted feeler arm carried by said stud and having one end extending transversely across said stud and adapted to swing in a horizontal plane and normally positioned to support said rod, the other end of said arm having a fabric engaging hole detecting finger, a belt shifting mechanism having a trip and means connected with said rod and operable by the downward movement thereof to engage said trip and actuate the belt shifter.

2. In a stop motion for knitting machines the combination with a belt shifting mechanism having a suitable trip, of a vertically slidable stop rod, a feeler arm pivotally engaged intermediate its ends to swing horizontally under and normally support said rod to hold it in raised position, and having a finger for engaging the fabric being knit, and means connected with said rod operable

on the downward movement of said rod to actuate said trip and operate the belt shifter.

3. In a stop motion for knitting machines, the combination with belt-shifting mecha-

nism having a suitable trip, of a vertically slidable stop rod, a feeler arm pivoted intermediate of its ends to swing horizontally, one end of said arm extending normally under said rod and holding it in raised position, a hole detecting fabric engaging finger on the other end of said arm, a crank shaft connected with said rod and adapted to be turned on the downward movement of said rod, and an element adjustably mounted on said shaft positioned to engage said trip on the turning of said shaft and actuate the belt shifter.

4. A stop motion for knitting machines, comprising a plate having an aperture therein for engagement with a center stud of a knitting machine, a curved strip having longitudinal slots at its ends and midway the length thereof, fastening elements passing through said slotted strip ends and engaged with the side edges of said plate for adjustably connecting said strip to said plate and in longitudinal alinement therewith, a laterally movable feeler arm pivoted intermediate of its ends to said plate with one end overlapping the aperture in said plate and with the other end extending through the center slot of said strip, a slidable rod resting normally on the inner end of said arm, and means connected with said rod for releasing a belt shifting trip lever.

In testimony whereof I have hereunto set my hand in presence of two subscribing witnesses.
